UNITED STATES PATENT OFFICE

ALBERT S. WALLACE, OF CHICAGO, ILLINOIS

RIM BREAKER

Application filed October 24, 1925. Serial No. 64,487.

This invention relates to a combined jack and rim tool and has for its object the provision of an efficient jack which may be used not only for lifting purposes but also as a means for quickly and easily removing a rim from the tire.

It is also an object of this invention to provide a jack which may be positioned under the member to be lifted without necessitating the operator's getting down into an uncomfortable and inconvenient position.

It is further an important object of this invention to provide a jack which has a removable base plate.

It is also an important object of this invention to provide a combined jack and rim tool which is simple and which may be economically manufactured and easily operated.

Other and further important objects of this invention will be apparent from the disclosures in the specification and the accompanying drawings.

This invention (in a preferred form) is illustrated in the drawings and hereinafter more fully described.

On the drawings:

Figure 1 represents a side elevational view of a jack embodying this invention, in operative position for use as a rim tool.

Figure 2 is an enlarged view with parts omitted of the device of Figure 1 in position for use as a jack, showing the removable base.

Figure 3 is a vertical sectional view with parts omitted taken at the line III—III of Figure 2.

Figure 4 is an enlarged fragmentary, horizontal, sectional view taken at the line IV—IV of Figure 1 with parts omitted.

Figure 5 is a horizontal, sectional view taken at the line V—V of Figure 2.

Figure 6 is a detail plan view of the extension for the jack crank showing the crank attached to said extension.

Figure 7 is an enlarged, detail, fragmentary, sectional view of the joint for the extension shown in Figure 6.

Figure 8 is an enlarged, detail, fragmentary, longitudinal section of the collar for connecting the extension shown in Figure 6 to the jack crank.

Figure 9 is a vertical, sectional view with parts omitted, taken at the line IX—IX of Figure 8.

Figure 10 is an enlarged, vertical section with parts omitted, taken at the line X—X of Figure 6.

As shown on the drawings:

Referring to Figure 2 of the drawings, there is shown a sleeve 1 which has near its upper end a pair of laterally extending, oppositely positioned ears 2 and adjacent its lower end a pair of similar ears 3. Each ear 2 is provided with a bearing socket 4 having an entrance neck and each ear 3 is provided with a bearing socket 5 having an entrance neck. The sockets 4 and 5 are similar. As shown in Figure 3 there is provided at the upper end of the sleeve 1 an integral yoke 6. The sleeve 1 is provided with a vertically extending, central aperture 7 for receiving the lower portion of a threaded bolt 8. The upper side of the yoke 6 is centrally apertured to permit the bolt 8 to extend upwardly therethrough. A diametrically extending pin 9 is secured in the lower end of the bolt 8 and slidably fits in suitable oppositely positioned vertical grooves 10 in the aperture 7. A screw member 11 threadedly engages the bolt 8 within the yoke 6 and rests upon a horizontal ring 12. The ring 12 with ball bearings 13 therebeneath and a similar ring 14 beneath said ball bearings forms a suitable ball bearing unit for supporting the screw 11. A horizontal gear 15 is provided at the lower edge of the screw 11 and is integral therewith. Extending into the side of the yoke 6 and journalled therein is a cylindrical member 16 which has rigidly secured thereto at its inner end a gear 17. The gear 17 meshes with the gear 15 for driving the latter. The cylindrical member 16 is provided with a central aperture 18 opening from its outer end and axially extending bayonet slots 19 diametrically positioned on opposite sides of the inner periphery of said aperture.

Mounted above the screw 11 and beneath the upper side of the yoke 6 is a second ball bearing unit 20 which is similar to the ball bearing unit previously described and designated by the reference numerals 12, 13 and 14.

14 indicating the upper ring, the ball bearings and the lower ring respectively of said unit 20. Secured on the upper end of the bolt 8 by a diametrically extending pin 21 5 is a shoe 22. The shoe 22 has a horizontal portion 23 and an upwardly and outwardly extending portion 24. The portion 24 has at its upper end a rearwardly extending hook portion 25. In addition to acting as a 10 shoe for ordinary lifting purposes, the shoe 22 is adapted to hook over the rim, the horizontal portion fitting the inner periphery of said rim, the portion 24 fitting the sloping side of said rim and the hook 25 engaging 15 over the edge of said rim. In using the jack as a rim tool, a pair of similar members 26 are used for engaging diverse points on the rim at the side of said rim opposite to the point engaged by the hook portion 23.

20 The members or arms 26, as shown in Figure 4, are each provided at one end with a transverse journal portion 27, and at the other end with a shoe 28 similar to the shoe 22. Each member 26 consists essentially of 25 the journal portion 27, the shoe 28 and the longitudinal supporting converging elements or members 29 which join the journal 27 at either end of the latter and connect the same to said shoe. A plurality of trans- 30 verse supporting members 30 are also provided longitudinally spaced between the elements 29.

In each member 26 there is provided inwardly of the journal 27, a transverse groove 31 or restricted portion extending across one 35 of the elements 29. The purpose of the groove 31 is to permit the journal 27 to enter any one of the bearing sockets 4 or 5 when at a given angular position and 40 aligned with said socket.

In the operation of removing a rim from the tire, the pair of members 26, as shown in Figure 1, are engaged in either the bearing sockets 4 or 5, depending upon whether 45 a rim of smaller or larger diameter is to be removed from its tire, and the shoes 28 are hooked over the edge of the rim. The shoe 22 on the bolt 8 is run out of the jack by turning the cylindrical member 16 sufficiently 50 to enable the latter shoe to hook over the side of the rim opposite to that engaged by the shoes 28.

The shoe 22 is preferably hooked over the rim near one of its ends. The jack crank 55 is then inserted in the cylindrical member 16 for rotating the latter and drawing the shoe 22 downwardly, removing the rim from the tire.

60 When the jack is used for lifting purposes it is desirable that means be provided so that said jack may be positioned underneath without necessitating the person using the jack getting under the car or other object to be lifted in any inconvenient position. 65 To accomplish this, there is provided a

collapsible extension 32 having legs 33 and 70 34 connected together by a hinge clip 35. The clip 35 is formed into a channel for receiving the ends of the legs 33 and 34. The leg 33 is held rigidly in the clip 35 against the bottom of the latter by means of a rivet or pin 36. The leg 34 is bent slightly at the end thereof, the bent portion being hinged in the clip 35 by means of a pin 37. The sides of the clip 35 below the pin 37 are 75 formed to extend inwardly as indicated in Figure 10 to resiliently lock the leg 34 when the latter is in the bottom of the clip 35 and in alignment with the leg 33.

The crank handle 38 for the jack, Figure 80 8, is provided with diametrically positioned, outwardly extending lugs 39 which are adapted to enter into the bayonet slots 19 of the cylindrical member 16 and lock said handle therein upon a slight rotation of said 85 handle. The upper end of the leg 33 is provided with lugs 40, similar to the lugs 39. The lower end of the leg 34 has pinned thereto a collar, the collar 41 being apertured to receive the crank 38 and provided on its 90 inner periphery with bayonet slots 42 similar to slots 19 for receiving and locking the lugs 39 on said crank.

Jacks for automotive vehicles are usually 95 stored when not in use in a manner which would make it inconvenient for them to have a very large base. In the case of automobiles, the jacks are frequently stored under the seat and consequently it would be very advantageous to have a removable base. For 100 this reason there is provided a large rectangular base plate 43 which is provided with a pair of upwardly extending longitudinally spaced lugs 44 on the upper side thereof adapted to fit on either side of one of the ears 3. A pair 105 of inwardly and upwardly extending lugs 45 are formed on the upper side of plate 43 and are positioned opposite to the lugs 44, a distance substantially equal to the width of the bottom of the sleeve 1. Between the upper ends of the lugs 45 is provided a journal 46 which is adapted to enter one of the bearing 110 sockets 5. One of the lugs 45 is provided with a restricted portion (not shown) similar to the groove 31 to permit the journal 46 to enter one of the bearing sockets 5 when the sleeve 1 is held in a definite angular position 115 with respect to the base plate 43. After the journal 46 enters one of the bearing sockets 5 the sleeve 1 may be pivoted about the journal 46 to bring the bottom of said sleeve against the upper side of the base plate 43, the ear 3 opposite to said journal entering between the lugs 44.

The operation of the device simply as a 120 jack is obvious. The operation of the device as a rim tool has been explained above. It will be apparent that the use of the above described device will enable many who have previously found it very inconvenient to re- 125 130

move and replace rims from tires to do so with very little trouble.

It will also be obvious that a great convenience is accomplished by providing a combined rim tool and jack, the function of a rim tool and a jack both being required in the actual removal of a rim from the tire.

I am aware that many changes may be made and numerous details of construction 10 may be varied through a wide range without departing from the principles of this invention, and I therefore do not purpose limiting the patent granted hereon, otherwise than necessitated by the prior art.

15 I claim as my invention:

In a rim tool, a frame comprising a substantially elongated sleeve, a threaded member normally housed within said sleeve and arranged for extensible and retractable movement with respect to the sleeve, being substantially co-extensive with the sleeve when in retracted position, co-operating means formed in the sleeve and at one end of said member for preventing the relative rotation 25 of the member with respect to the sleeve during the extensible and retractable movements of the member within the sleeve, said member having a rim engaging portion at its opposite end, means carried at one end of said sleeve for effecting extensible and retractable movements of the member within the sleeve and rim engaging arms pivoted to said sleeve at points intermediate its ends.

In testimony whereof I have hereunto subscribed my name.

ALBERT S. WALLACE.
